UNITED STATES PATENT OFFICE

HENRY CAVE, OF HARTFORD, CONNECTICUT, ASSIGNOR TO THE FULLER BRUSH COMPANY, OF HARTFORD, CONNECTICUT, A CORPORATION OF CONNECTICUT

BRUSH STRIP FORMING MACHINE

Application filed November 13, 1926. Serial No. 148,281.

My invention relates to mechanism for controlling the feed of bristles or similar brush materials to a base piece or holding strip to which said material is secured, the whole being intended for subsequent use in the making of brushes, and an object of my invention, among others, is the production of mechanism whereby the feed of material to a holding strip or base may be varied from a continuous even feed to an interrupted variable feed, whereby sections of different thickness of bristles may be obtained and whereby sections devoid of bristles, thereby providing spaces, are obtained and whereby the lengths of such sections and spaces may be varied to suit any special requirement.

One form of machine embodying my invention and in the construction and use of which the objects herein set out, as well as others, may be attained, is illustrated in the accompanying drawings, in which—

Figure 1 is a view in rear elevation of a machine embodying my invention.

Figure 2 is a top view of the same with parts broken away to show construction, omitting the folding disc.

Figure 3 is an end view looking at the right hand end of the machine as seen in Figure 1.

Figure 4 is a detail view illustrating the construction and operation of the spacing mechanism.

Figure 5 is a detail view of a portion of a brush strip produced by my improved machine.

Figure 6 is a view of a brush length cut from said strip, and

Figure 7 is a view of a completed brush formed from a brush length cut from a brush strip produced by my improved machine.

Figure 8 is a detail view illustrating the operation of tucking the ends of bristles into the holding strip.

Figure 9 is a cross sectional view of the holding strip with the ends of the bristles tucked therein.

In the accompanying drawings the numeral 5 indicates the base or bed of my improved machine that may be supported in any suitable or desired manner and that has mounted thereon at or near one end a table 6 from which a pedestal 7 rises, which pedestal comprises a support for a hopper 8 adapted to contain bristles or other brush making material, the construction and operation of which hopper, together with mechanism for conveying the bristles therefrom is fully set forth and disclosed in my copending application filed February 16, 1926, of Serial Number 88,711.

A driving shaft supporting arm 9 is secured at its lower end to a rock shaft 10 mounted in brackets 11 attached to the table 6, a driving shaft 12 being mounted in a bearing in the upper end of the arm and having a driving pulley 13 adapted to receive a driving belt 14 extending to any suitable source of power. The shaft 12 has driving discs 15 attached thereto, the peripheries of said discs projecting into spaces between clutch discs 16 secured to a feed shaft 17 in a manner to move lengthwise of said shaft to a slight extent but to rotate said shaft, one member 18 of said clutch discs being engaged by a forked clutch actuating lever 19 to be hereinafter described. Said discs are forced apart or disengaged in any suitable manner, manually or mechanically.

A feed disc 20 is secured to the shaft 17 and is provided with notches 21 in its periphery that projects into the lower end of the hopper 8 and by means of which bristles or other brush material is, in the rotation of said disc, taken from the hopper and deposited upon feed belts 22—23 arranged preferably in pairs, one pair being located above the other and the brush material being carried between them. Said belts are mounted at their opposite ends upon rolls supported in any suitable manner, the belts 23 being driven by frictional contact with the brush

material or with the belts 22 when there is no material between the belts. The rolls 24 for supporting one end of each of the belts 22 are each rotatably mounted on the upper end of an arm 25, the lower end of which is 5 pivotally adjustably secured to the bracket 11. A shaft 26 supporting the rolls for the belts 22 is rotatably mounted in the bracket 11, said rolls being secured to said shaft, and the latter being driven as by means of a 10 gear 27 secured to the shaft and meshing with a gear, not shown, forming a part of the mechanism of the machine.

The parts thus far described form the subject matter of my copending application 15 hereinbefore referred to and for which reason a general description only is given herein, a specific and detailed description not being necessary for a complete understanding of the invention, and said copending application 20 being referred to for any further description that may be desired.

Said machine in its general construction further embodies means for feeding a strip or holding piece 28 having a groove into 25 which the bristles 29 are forced by bending or folding, as by the action of a folding disc 30 rotatably mounted and from which the strip with said bristles folded therein is 30 passed between pressing rolls 31, as more particularly set forth and claimed in my copending application filed December 14, 1925, of Serial Number 75,219, and to which reference is hereby made for a more complete understanding, if desired. The disc 30 conducts a wire 94 into the fold of the bristles 35 as an aid in retaining them in the strip 28.

My improved machine is intended for the formation of brush strips of indefinite lengths, which strips are cut into suitable 40 lengths by mechanism which may or may not comprise a part of the machine as a whole. In the construction of many brushes it is desired that the end or ends of the brush lengths 32 cut from the strip 33 shall be free 45 from brush material for various reasons, as for the reception within a handle 34 of a brush, as shown in Figure 7. Therefore, my improved machine is provided with means 50 for automatically creating spaces 35 in the formation of the strip 33.

It is also desirable in some cases to provide thick sections 36 at more or less regular intervals in the formation of the strip 33, such 55 thick sections, as one instance of use, providing a thickened end 37 in a brush 38, and as shown in Figure 7. My improved machine is therefore provided with means for automatically accomplishing these purposes in 60 the formation of the brush strips, said mechanism controlling the feed of brush material to the strip 28 and including a driving pulley 39 secured to a driving shaft 40 mounted in bearings in brackets on the base 5, said shaft 65 having a pinion 41 meshing with a gear 42

mounted on said base, the shaft of said gear being connected by mechanism (not herein shown) to drive other mechanisms including the pressing rolls 31, knowledge of said connection not being necessary for a thorough 70 understanding of the present invention, but which connection is shown in my hereinbefore mentioned copending application S. No. 75,219, and to which reference is hereby again made for such further understanding 75 as may be desired.

The mechanism just hereinbefore described is a controller mechanism for which controller driving mechanism is provided, such driving mechanism including a gear 42 80 meshing with a pinion 43 secured to a clutch driving shaft 44 mounted in bearings in brackets secured to the base 5 and having clutch discs 45 loosely secured thereto to rotate therewith but having a slight endwise 85 movement thereon as do the discs 15 hereinbefore mentioned, said discs 45 projecting into the spaces between clutch discs 46 loosely supported by a clutch shaft 47 but engaged with said shaft to rotate it, said discs 46 90 being spring pressed toward each other in a manner well known in structures of this kind, and as shown in dotted lines in Figure 1. One of the outside discs 46 has a grooved clutch actuating collar 48 for engagement 95 with one arm of a clutch actuating lever 49 pivotally mounted on the end of an arm 50 extending from one end of a bracket 51 secured to the base 5.

The controller mechanism embodies mechanism for determining the length of the brush sections and this includes the shaft 47 mounted in bearings on a swinging support 52, the lower end of which is pivotally attached to a feed controlling shaft 53 mounted 100 in the arm 50 and in an arm 54 projecting from the bracket 51. The upper end of the support 52 has a block 55 pivotally attached thereto and having a threaded hole engaged by a screw threaded adjusting rod 56 extending through and rotatably mounted in a supporting block 57 pivotally attached to a supporting bracket 58 secured to a post 59 rising from the base 5 and secured thereto at its lower end, as by means of a nut, as shown in 105 Figure 3 of the drawings. An adjusting hand wheel 60 secured to the end of the rod 56 is employed for rotating the latter, this end of said rod being secured against independent movement lengthwise of the block 57 but being freely rotatable therein whereby rotation of the hand wheel causes the support 52 to swing on its pivot for the purpose of adjusting the relative positions of the discs 45 and 46 and thereby varying the speed of rotation of the shaft 47. A telescoping indicating rod 61 is secured to the blocks 55 and 57, the outer section of the rod having an opening for view of graduations 95 on the other section, and the engage- 110

115

120

125

130

ment of the rod sections being loose enough if need be to permit the necessary swinging movement of the blocks in the adjustment of the support 52.

The controller mechanism further embodies a spacing mechanism that includes the shaft 47 having a pinion 62 meshing with a gear 63 secured to the controlling shaft 53, whereby the latter is rotated for the purpose of operating the mechanisms for controlling the length of the spaces 35 relatively to the portions 29 and 36 and thereby determining the relative lengths of the portions 29 and 36 of the brush strip. To accomplish this purpose the feed of the bristles by the disc 20 is interrupted at intervals after which the feed again takes place and this is effected by operation of the clutch discs 15 and 16 by means of feed controlling pins 64-65 projecting from discs 66 secured to and resting against opposite sides of the gear 63, said pins being positioned to engage feed controlling fingers 67-68 secured to and projecting from a feed controlling sleeve 69 mounted for rocking movement on a shaft secured in the arm 54 and an extension 70 from the bracket 51. The finger 68 is connected by a link 71 with an arm 72 projecting from a rock shaft 73 mounted at opposite ends in the arm 54 and in a bracket 74 secured to the bed 5. The end of the shaft opposite the arm 72 has a toe 75 in engagement with an arm 76 of the actuating lever 19. The pins 64 and 65 are adjustably mounted in slots in the discs 66, as shown in Figures 3 and 4, and by properly positioning these pins the time of their engagement with the fingers 67 and 68 to secure and release the clutch discs 15 and 16 may be regulated to obtain such widths of the spaces 35 as may be desired.

Engagement of the pin 65 with the finger 68 rocks the shaft 73 and moves the toe 75 to a position to act upon the lever 19 and force the discs 16 apart against the tension of their spring, which spring may be arranged in a manner similar to that shown in dotted lines within the collar 48 in Figure 1, and the movement of the sleeve 69 may be effected by a spring 77. A handle 98 is secured to the lever 19 for manual actuation thereof when desired. The finger 68, when moved by the pin 65 to its lowest position, will locate the pivotal point of attachment of the link 71 to said finger just beyond a line passing through the centers of the shaft 81 on which said finger is mounted and the pivot connecting said link to the arm 72, whereby the finger will remain in this position until the pin 64 engaging the finger 67 moves said pivotal point back to the opposite side of said line, at which time the spring 77 will snap the finger 67 to its opposite position and as shown in Figure 3 of the drawings. This operation releases the toe 75 from the arm 76 permitting

the spring for the discs 16 to force the discs 15 and 16 into driving contact.

From the foregoing description it will be seen that by manual operation of the hand wheel 60 the discs 45-46 may be adjusted for engagement in a manner to lengthen or shorten the brush lengths 32, and by adjusting the position of the pins 64-65 the width of the spaces 35 may be determined.

The controller mechanism further embodies tufting mechanism for producing the thick sections or tufts 36, this being done by manipulation of the discs 15-16 to swing them toward or from each other, said tufting mechanism including a rocker rod 78 extending through the arm 9, with a spring 79 at one end for rocking the arm in one direction and a rocker lever 80 connected with the opposite end of said arm to rock it in the opposite direction, the lever 80 being secured to a sleeve mounted on a shaft 81 on which the sleeve 69 is mounted. This lever 80 has a roller in contact with a cam secured to the shaft 53 and comprising two members 82-83 adjustably connected and the latter having a collar 84 loosely fitting the shaft 53. The member 82 loosely fits upon the shaft 53 and is secured to said shaft as by means of a hook 90 secured at one end to said member as by means of a nut that draws the opposite and hooked end into tight contact with a collar 91 secured to the shaft 53. When this cam engages the lever 80 the arm 9 is rocked to move the discs 15-16 apart, thus increasing the rate of rotation of the feed disc 20 and thereby producing the thickened sections 36, and the length of these thickened sections will depend on the width of the cam comprising the combined length of the ends of the members 82-83 as determined by the relative positions of said members. By varying the relative positions of the cam members 82-83 the lengths of the tufts 36 may be varied as desired.

If it be desired to produce a strip with the bristles continuous and of even thickness the lever 49 may be rocked by operation of an eccentric pin 85 on a clutch disconnecting shaft 86 mounted at one end in the arm 50 and at its opposite end in a bearing 92 secured to the base 5 and as shown in Figure 1 of the drawings. A handle 93 projects from the shaft 86 as a means for manually operating it.

The relative positions of the discs 15 and 16 are adjusted to vary the speed of the disc 20 and thereby obtain the desired thickness of the thin portions 29 of the bristles by an adjusting screw 87 threaded fitting in the table 6 and having an adjustable stop 88 against which a lever 89 rests, said lever being secured to the shaft 10 and being held against said stop by the spring 79. The position of the stop 88 will determine the thick-

ness of the thin portion of the bristles and by changing the position of this stop by turning the screw out or in such thickness may be varied at will. It may be noted that this 5 adjustment will not change the thickness of the thick section 36 of the strip for the reason that the adjustment slackens the flexible connection 96, which slack is immediately taken up when the cam (82-83) engages the 10 lever 80. However, the thickness of the thick section 36 may be correspondingly increased by taking up the slack of the chain or flexible connection by means of an adjustable connection 97 shown in Figure 1.

15 The controlling mechanism hereinbefore described and comprising the members borne by the shaft 53 and also connected therewith for operation thereof and to be operated thereby, is for the purpose of effecting the 20 formation of brush strips as shown in Figure 6, each cycle of movement of such controlling mechanism, that comprises a complete rotation of the shaft 53, being effective to produce such a strip. If the speed of this 25 controlling mechanism be varied without changing the rate of travel of the holding strip 28 the length of the brush lengths 32 will be accordingly varied. This change in speed of controlling mechanism is obtained 30 by changing the length of the indicating rod 61 as by means of the hand wheel 60 screwing the rod 56 into the block 55, the graduations 95 on the rod 61 indicating the length of the strip to be produced in this operation. 35

40 After the length of the strip has been determined by means of said indicating rod the relative lengths of the brush sections and of the spaces between them may be fixed by means of the pins 64-65. By locating the pins nearer together in the direction of the least space between them, as shown in Figures 3 and 4, the length of the space 35 will be decreased and the lengths of the combined brush sections 29 and 36 will be increased. 45

50 The length of the combined brush sections 29 and 36 having been thus determined the positions of the sections 36 in the sections 55 29 may be fixed by adjusting the position of the cams 82-83 on the shaft 53, thereby determining the time of operation of the lever 19 to operate the discs 15-16 to increase or decrease the speed of the disc 20 to increase or 60 decrease the thickness of the bristles, as at 36, and the relative positions of the cams 82-83 may be changed to increase or decrease the length of the operating edge of said combined cams to increase or decrease 65 the length of time of speeding up of the disc 20 to increase or decrease the length of the brush sections 36, which increase in length of said sections 36 will decrease the length of the brush sections 29.

70 75 80 85 90 95 100 105 110 115 120 125 130 135

55 In the mechanism hereinbefore described

the bristles are fed to the holding strip 28 substantially at their lengthwise centers, whereby both ends of the bristles project to substantially the same extent and both the butts and "flags" of the bristles, therefore, comprise the edge of the brush. The flags, which are the tips of the bristles, are finer than the butts, and it is, therefore, desirable in some instances to produce a brush of extremely soft construction and composed entirely of the flags or tips of the bristles. This may be done by arranging the bristles with the tips all extending in one direction and by placing the bristles between the belts 22-23 with the butts located over the holding strip 28. In this disposition the butts of the bristles are tucked into the holding strip as shown in Figure 9, and the flags or tips of the bristles comprise the end of the brush.

90 95 100 105 110 115 120 125 130 135

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim—

1. A brush strip making machine including means for moving a holding strip, means for feeding brush material to said strip, and means for controlling the feeding means by intermittently varying the amount of brush material delivered to the holding strip. 100

2. A brush strip making machine including means for feeding a holding strip at a constant speed, means for delivering brush material to said strip, and a variable speed drive periodically affected by power driven means for varying the operating speed of said delivering means to vary the amount of the brush material delivered to said holding strip. 105

3. A brush strip making machine including means for moving a holding strip at a uniform speed, means for feeding brush material to said strip at a uniform speed, and a controller mechanism including a periodically actuated clutch for intermittently stopping the operation of the brush material feeding means while the holding strip continues to move to provide spaces in the made strip. 110

4. A brush strip making machine including means for moving a holding strip, means for feeding brush material to said strip, and a controller mechanism including members for intermittently effecting a variation in the speed of operation of the brush material feeding means for correspondingly varying the amount of material delivered to the holding strip, and also including means for intermittently stopping the operation of the said feeding means to provide spaces in the made strip. 120

5. A brush strip making machine includ-

- ing means for feeding a holding strip at a uniform speed, means for feeding brush material to said strip at a speed predetermined with respect to the speed of the strip, means 5 for securing the material in said strip and a controller mechanism including members for intermittently varying the speed of operation of one of said feeding means for correspondingly varying the amount of material delivered to a predetermined portion of said strip, and also members for intermittently stopping the operation of the said feeding means to provide spaces in the made strip. 10
6. A brush strip making machine including means for feeding a holding strip, means for feeding brush material to said strip, controller mechanism for varying the operation of the brush material feeding means for correspondingly varying the feed of material to 15 said strip, and means for operating said controller mechanism independently of said brush material feeding means. 20
7. A brush strip making machine including means for moving a holding strip, means for feeding brush material to said strip, means for securing said material in said strip, a controller mechanism operatively connected with said material feeding means, means for driving said controller mechanism at variable rates of speed, and means for adjusting said driving means to determine the rate of speed of said controller mechanism. 25
8. A brush strip making machine including means for moving a holding strip, means for feeding brush material to said strip, a controller mechanism operatively connected with said material feeding means, means for driving said controller mechanism at variable rates of speed, and manually actuated means for adjusting said driving means to determine the rate of speed of said controller mechanism. 30
9. A brush strip making machine including means for moving a holding strip, means for feeding brush material to said strip, means for securing brush material in said strip, a controller mechanism operatively connected with said material feeding means, means for driving said controller mechanism at variable rates of speed, and means for adjusting said driving means to vary the rate of speed of said controller mechanism and to retain said adjusting means in different positions of adjustment, said adjusting means including a driving element support movably mounted and an actuator for said support. 35
10. A brush strip making machine including means for moving a holding strip, means for feeding brush material to said strip, means for securing said material in said strip, a controller mechanism operatively connected with said feeding means for producing successive brush material sections duplicates of 40
- one another in said strip, means for driving said controller mechanism at variable rates of speed, means for adjusting said driving means to vary the rate of speed of said controller mechanism, and means for indicating the rate of speed at which said controller mechanism is run and to thereby denote the length of said duplicate sections of the brush material. 45
11. A brush strip making machine including means for moving a holding strip, means for feeding brush material to said strip, means for securing said material in said strip, a controller mechanism operatively connected with said material feeding means to automatically vary its feeding operation, means for driving said controller mechanism, and means for disconnecting said driving means from said controller mechanism to discontinue the automatic production of variations in the operation of the material feeding means so as to permit the feeding means to effect a continuous even feed of said material to said brush strip. 50
12. A brush strip making machine including means for moving a holding strip, means for feeding brush material to said strip, means for securing said material in said strip, a controller mechanism operatively connected with said material feeding means to automatically vary its feeding operation, means for driving said controller mechanism at variable rates of speed, said last mentioned means including a swinging support for a portion of said driving means which portion is movable with respect to a different portion of said driving means to produce the variations in the rate of speed and a manually actuated screw threaded rod connected with said support to effect swinging movement of the latter. 55
13. A brush strip making machine including means for moving a holding strip, means for feeding brush material to said strip, means for securing said material in said strip, a controller mechanism operatively connected with said material feeding means to automatically vary its feeding operation, means for driving said controller mechanism at variable rates of speed, said last mentioned means including a swinging support for a portion of said driving means, which portion is movable with respect to a different portion of said driving means to produce the variations in the rate of speed, a manually actuated screw threaded rod connected with said support to effect swinging movement thereof, and means for denoting the position of said swinging support. 60
14. A brush strip making machine including means for moving a holding strip, means for feeding brush material to said strip, means for securing said material in said strip, a controller mechanism operatively connected with said material feeding means, to automat- 65

ically vary its feeding operation, means for driving said controller mechanism at variable rates of speed, said last mentioned means including a swinging support for a portion of said driving means, which portion is movable with respect to a different portion of said driving means to produce the variations in the rate of speed, means for swinging said support and for retaining the latter in different positions to vary the rate of speed of said controller mechanism, and a telescoping indicating rod having markings and connected with said support to denote its position.

15. A brush strip making machine including means for moving a holding strip, means for feeding brush material to said strip, a controller mechanism operatively connected with said material feeding means to automatically vary its feeding operation, means for driving said controller mechanism at variable rates of speed, said last mentioned means including a swinging support for a portion of said driving means, which portion is movable with respect to a different portion of said driving means to produce the variations in the rate of speed, an adjusting rod having screw threads engaging said swinging support, a support in which said rod is rotatably mounted and held against lengthwise movement, a telescoping indicating rod secured to said swinging support and to the support for said rod, and means on the inner section of said rod and movable with respect to the outer section for indicating the speed at which the controller mechanism shall be run.

16. A brush strip making machine including means for moving a holding strip, means for feeding brush material to said strip, means for regulating the action of said feeding means to change the feed of said material, means for securing said material in said strip, and a mechanism including members operatively connected with said regulating means to intermittently operate the latter.

17. A brush strip making machine including means for moving a holding strip, means for feeding brush material to said strip, means for securing said material in said strip, means for stopping the feed of said material, and a mechanism including members operatively connected with said feeding means to change the rate of feed of said material.

18. A brush strip making machine including means for moving a holding strip, means for feeding material to said strip, and means for securing said material in said strip, means for stopping the feed of said material, said stopping means comprising a clutch and a controller mechanism for the clutch including a rotating member driven at a predetermined speed, a rocking member to be engaged and actuated by said rotating member, and

means operatively connecting said rocking member to the clutch.

19. A brush strip making machine including means for moving a holding strip, means for feeding brush material to said strip, means for securing said material in said strip, means for starting and stopping the operation of said material feeding means, and a controller mechanism for the starting and stopping means including a rotating disc, pins relatively adjustably secured to said disc, and a rocking member adapted to be engaged by said pins and operatively connected with said feed starting and stopping means to control the operation of the latter.

20. A brush strip making machine including means for moving a holding strip, means for feeding brush material to said strip, means for starting and stopping the operation of said material feeding means, and a controller mechanism for the starting and stopping means including a rotating disc having pins projecting therefrom, and a rocking member having fingers to be engaged by each of said pins and operatively connected to control the operations of said feed starting and stopping means.

21. A brush strip making machine including means for moving a holding strip, means for feeding brush material to said strip, means for securing said material in said strip, clutch means for starting and stopping the operation of said material feeding means, and a controller mechanism for the clutch means including a rotating disc, a rockingly mounted sleeve having fingers positioned for intermittent engagement by said disc to be operated thereby, and an operative connection between said sleeve and said clutch means for operation thereof to control the feed of said material.

22. A brush strip making machine including means for moving a holding strip, means for feeding brush material to said strip, means for securing said material in said strip, means for starting and stopping the operation of said material feeding means, and a controller mechanism for the starting and stopping means including a rotating disc, a rockingly mounted member positioned for operation by said disc, a connection between said rocking member and said starting and stopping means for operation of the latter, and means for retaining said rocking member in one position when moved thereto by said disc.

23. A brush strip making machine including means for moving a holding strip, means for feeding brush material to said strip, means for securing said material in said strip, means for starting and stopping the feed of said material, and a controller mechanism for the last mentioned means including a rotating disc, a rocking member operatively

positioned for connection with said disc to be rocked in opposite directions thereby, means for retaining said rocking member in one position, and means for aiding its 5 movement to another position.

24. A brush strip making machine including means for moving a holding strip, means for feeding brush material to said strip, means including a clutch for starting and 10 stopping the feed of said material, and a controller mechanism for the last mentioned means including a rocking shaft operatively connected with said clutch, a rotating disc, and an operative connection between said 15 disc and rocking shaft for operation of the latter to operate said clutch.

25. A brush strip making machine including means for moving a holding strip, means for feeding brush material to said strip and 20 including a feeding member, means for securing said material in said strip, means for changing the speed of operation of said feeding member, and a controller mechanism for the last mentioned means including a movably mounted member, and a connection between said member and said speed changing means to cause the movement of said member to control the speed of the brush material 25 feeding means.

30 26. A brush strip making machine including means for moving a holding strip, a feeding member for feeding brush material to said strip, means for securing said material in said strip, means for changing the speed of 35 operation of said feeding member, and a controller mechanism for the last mentioned means including a driven controller cam, and an operative connection between said cam and said speed changing means to cause the action 40 of the cam upon the connection to control the speed of the latter.

27. A brush strip making machine including means for moving a holding strip, a feeding member for feeding brush material to 45 said strip, means for securing said material in said strip, means for changing the rate of speed of said feeding member and including a rocking member, and a controller mechanism for the last mentioned means including a movably mounted member, and an operative connection between said movably 50 mounted member and said rocking member.

28. A brush strip making machine including means for moving a holding strip, a feeding member for feeding brush material to said strip, means for securing said material in said strip, means for changing the rate of speed of said feeding member and including a rocking member, and a controller mechanism for the last mentioned means including a rocker lever operatively connected with 55 said rocking member, and a cam to engage said lever to operate it.

29. A brush strip making machine including means for moving a holding strip, a feed

member for feeding brush material to said strip, means for securing said material in said strip, means for changing the speed of operation of said feed member, and a control for the speed changing means including a rotatably mounted shaft, a cam secured to said shaft, means for changing the length of the active edge of said cam, and an operative connection between said cam and said speed changing means for operation of the latter to vary the rate of feed of said material. 70 75

30. A brush strip making machine including means for moving a holding strip, a feeding member for feeding brush material to said strip, means for securing said material in said strip, means for changing the speed of operation of said feeding member, and a control for the speed changing means including a movably mounted feed controller member, a sectional operating member secured to said feed controller member, means for adjusting the relative positions of the sections of said operating member to vary the length of time of operation by them, and an operative connection between said operating member and said speed changing means for operation of the latter to vary the rate of feed of said material. 80 85 90

31. A brush strip making machine including means for moving a holding strip, a feeding member for feeding brush material to said strip, means for changing the speed of operation of said feeding member, and a control for the speed changing means including a rotatably mounted shaft, a sectional cam secured to said shaft, means for changing the relative positions of the sections of said cam to vary the length of the active edge thereon, and an operative connection between said cam and said speed changing means for operation of the latter to vary the rate of feed of said material. 95 100 105

32. A brush strip making machine including means for moving a holding strip, a feeding member for feeding brush material to said strip, means for securing said material in said strip, means for stopping the movement of said feeding member, means for varying the rate of movement of said feeding member, and a controller including a movably mounted feed controller member, feed stop actuating mechanism borne by said feed controller member, a speed change actuating member borne by said feed controller member, an operative connection between said feed stop actuating mechanism and said feed stopping means, and an operative connection between said speed change actuating mechanism and said rate varying means. 110 115 120 125

33. A brush strip making machine including means for moving a holding strip, a feeding member for feeding brush material to said strip, means for securing said material in said strip, means for stopping the move-

ment of said feeding member, means for varying the rate of movement of said feeding member, and a controller including a rotatably mounted shaft, a feed stop controller member secured to said shaft, a speed change controller member secured to said shaft, an operative connection between said feed stop controller member and said feed stopping means, and an operative connection between 5 said speed change controller member and said 10 rate varying means.
